UNITED STATES PATENT OFFICE.

SAMUEL J. SORENSEN, OF LONG BEACH, CALIFORNIA.

STRAINER.

Application filed April 30, 1925. Serial No. 26,881.

This invention relates to improvements in strainers.

An object of this invention is to provide an improved strainer consisting of a cup-like body which is vertically divided to form two complementary halves capable of being separated so as to facilitate cleaning of the strainer.

It has been experienced that strainers which are usually employed in cooking for straining gravy, sauces, soups and the like are very difficult to clean. This results for the reason that the strainer is generally in the form of a cup-like body and frequently is in the form of a cone. When sticky substances are strained, which upon cooling thicken or harden, it is very difficult to thoroughly clean the bottom of the strainer, because of the tapered or convergent side walls of the strainer, which prevent the efficient use of a wash cloth or other cleaning device.

By the improved construction the halves of the strainer can be opened or separated from each other, so that the bottom of the strainer can be easily and readily cleaned.

With the foregoing and other objects in view which will be made manifest in the following detailed description and specifically pointed out in the appended claims, reference is had to the accompanying drawings for an illustrative embodiment of the invention, wherein:

Figure 1 is a perspective view of one form of strainer upon which my invention has been embodied,

Fig. 2 is a view in elevation taken in the direction of the arrow 2 upon Fig. 1,

Fig. 3 is a view in elevation taken in the direction of the arrow 3 upon Fig. 1,

Fig. 4 is a horizontal section taken upon the line 4-4 of Fig. 2, and

Fig. 5 is a horizontal section taken upon the line 5-5 of Fig. 3.

Referring to the accompanying drawings wherein similar reference characters designate similar parts throughout, the invention is shown as embodied upon a conical strainer of somewhat conventional construction, although the invention may be embodied upon other types of strainers used for similar purposes. The strainer illustrated consists of an annular ring 10, which has a hook 11 formed upon its forward side and is provided with a handle 12 at its back. A conical tip 13 is also provided and is held

in spaced relation below the ring 10 by reinforcing rods 14 which are rigidly fastened to the ring 10 and to the conical tip 13. A foraminous material 15 is arranged between the ring 10 and the tip 13 so as to form porous side walls for the strainer. This foraminous material is not limited to any particular form of construction, and although the drawing illustrates the use of woven wire or screen, it is contemplated within the scope of the invention to employ other material, as, for example, perforated sheet metal.

The ring 10, the foraminous material 15 and the conical tip 13 are vertically divided so as to form two complementary halves. The adjacent edges indicated at 16 and 17 upon Fig. 5 are fastened together as by a hinge 18, which permits the complementary halves to be swung apart from each other, so that the bottom of the strainer can be easily cleaned. A suitable latching device 19 is mounted upon the swinging ends of the halves of the ring 10 for detachably fastening the hinged complementary halves together. This latch device can be of any conventional construction, and is illustrated upon the drawing as consisting of a stud or keeper 20 which is adapted to be engaged by a U-shaped yoke 21, which is pivoted as at 22.

In order to prevent leakage at the places where the strainer is divided, one edge of each pair of adjacent edges is so constructed as to overlap its adjacent edge. This construction is provided by enclosing one edge of each adjacent pair by a channel shaped strip of sheet metal 23. The opposite edge is covered by a channel shaped strip of sheet metal 24, which has its inner corner reversely bent upon itself, as indicated at 25, to form an overlap. As clearly indicated in Figs. 4 and 5, this construction is provided upon both sides of the strainer, so that there can be no leakage where the body of the strainer is divided.

By the improved construction, it will be readily appreciated that the halves of the strainer can be fastened together while used for straining and that after the substance has been strained, the halves may be detached and swung apart so as to enable the strainer to be easily, quickly and thoroughly cleaned.

It will be understood that various changes may be made in the detail of construction without departing from the spirit and scope

of the invention as defined by the appended claims.

I claim:

1. A strainer comprising an open topped cup-like body formed of foraminous material, said body being vertically divided to form two complemental parts, means for hingedly fastening one pair of adjacent edges upon said parts together, and means for detachably securing the other pair of adjacent edges upon said parts together.
2. A strainer comprising an open-topped cup-like body formed of foraminous material, said body being vertically divided to form two complemental parts, means for hingedly fastening one pair of adjacent edges upon said parts together, and means for detachably securing the other pair of adjacent edges upon said parts together, one of the edges of each pair of adjacent edges being so constructed as to overlap the adjacent edge.
3. A strainer comprising an annular ring and a bottom conical tip, rods connecting

said ring and tip, a foraminous material connecting said ring and tip, said ring, tip and foraminous material being vertically divided to form two complemental halves, means for hingedly securing one pair of adjacent edges upon said halves together, and means for detachably securing the other pair of adjacent edges upon said halves together.

4. A strainer comprising an annular ring and a bottom conical tip, rods connecting said ring and tip, a foraminous material connecting said ring and tip, said ring, tip and foraminous material being vertically divided to form two complemental halves, means for hingedly securing one pair of adjacent edges upon said halves together, and means for detachably securing the other pair of adjacent edges upon said halves together, one edge of each pair of edges being so constructed as to overlap its adjacent edge so as to prevent leakage.

In testimony whereof I have signed my name to this specification.

SAMUEL J. SORENSEN.
